GAS BURNERS

Philip M. Forniti, Cleveland, Ohio, assignor to Hupp Corporation, Detroit, Mich., a corporation of Virginia

Application August 10, 1956, Serial No. 603,390

1 Claim. (Cl. 126—92)

This invention relates to burners and more particularly to gas burners.

While the invention is, in certain aspects, of broad utility and application, for present purposes it will be disclosed as applied to improved burners for the generation of infra-red heat of the so-called flameless type in which combustion of gaseous fuel and air takes place in the outer surface of the burner element.

For maximum efficiency such burners should operate in substantially still air and the efficiency of such heaters is seriously reduced when the burner surfaces are exposed to currents of moving air. For example, particularly in outdoor installations, gusts of wind blowing against the combustion surface will cause eruptions of flame from the surface, lowering the temperature of the burner surface thereby seriously reducing the rate of emission of radiant energy. Even indoors such burners are often subject to such currents of air which may be produced by ventilators, open doors or other sources.

In many cases radiant burners or heaters of this type are provided with a duct leading away from the burner surface to confine and direct the radiant energy. Such a duct, if it is imperforate and leads directly from the burner surface, will provide substantial protection against air currents. However, experience has shown that the combustion products cannot be satisfactorily evacuated if such an imperforate shield or duct is used particularly in view of the fact that in most cases the burners are positioned overhead, with the burner surface and the associated duct pointing downwardly.

Accordingly, such shields or ducts have been provided with suitable openings to promote the evacuation of the combustion products with the result that the ducts no longer provide the required protection of the burner surfaces against air currents.

It has also been discovered that random air currents can also adversely affect the combustion efficiency of burners of this type if they are allowed to enter the region of the burner adjacent the air intake. While various shields have been proposed in the past to protect the air inlet from random air currents and varying wind pressures, nevertheless, no satisfactory solution of this problem has been proposed prior to the present invention.

With the foregoing considerations in mind it is the principal purpose and object of the present invention to provide improved radiant heat burners which are fully protected against wind currents and which operate with near optimum efficiency even in high winds.

In accomplishing this and other objects the invention contemplates the provision of a heat directing duct assembly leading away from the surface of the burner and a secondary duct system extending transversely across the primary heat directing duct assembly which permits effective evacuation of the combustion products and yet fully protects the surfaces of the burner against wind currents. In the preferred form of the invention, one wall of the secondary duct comprises the radiant burner

2

surfaces and the opposite duct wall comprises an imperforate sheet of material which is transparent to the radiant energy which it is desired to transmit in a given application. The present invention further contemplates the provision of a novel shield assembly surrounding the combustion air intake to protect the latter against excessive air currents. The shield and the secondary duct system cooperate in a novel manner to provide a fully windproof burner assembly.

10 It is accordingly a further object of the present invention to provide improved radiant heat burners which may be used outdoors and under conditions where previous burners of this type have proved to be unsatisfactory.

It is also an object of the present invention to provide novel shield assemblies for radiant heat burners which effectively neutralize varying wind pressures from all directions and provide substantially constant pressure at the air inlet so that the combustion air is entrained at a uniform rate for maximum combustion efficiency.

20 It is a further object of the present invention to provide novel shield assemblies for radiant heat burners which are of simple, durable construction and which may be manufactured at low cost.

Additional objects and advantages will become apparent as the description proceeds in connection with the accompanying drawings in which:

Figure 1 is a side elevation with parts broken away of an improved burner constructed in accordance with the present invention;

30 Figure 2 is a top plan view of the burner of Figure 1; Figure 3 is a transverse section of the burner taken along line 3—3 of Figure 1; Figure 4 is a fragmentary section taken along line 4—4 of Figure 1;

35 Figure 5 is a section taken along line 5—5 of Figure 1 and showing details of the air intake shield; and Figure 6 is a side elevation of the shield assembly shown in Figure 5.

Referring now more particularly to the drawings, the 40 principal components of the burner therein shown are the burner heads 20 and 22, the main heat directing duct assembly 24 including a duct member 25, the secondary ventilation duct assembly 26 which extends across and forms a part of the duct assembly 24 and the air intake shield assembly 28. The burner heads 20 and 22 are secured by a plurality of bolts 30 to a frame structure 32 which extends around the periphery of the two burner heads and between the two burner heads. Preferably an attaching bracket 34 is secured to the frame 45 assembly 32 between the adjacent edges of the two burners.

45 Each of the burner heads 20 and 22 comprises a housing 36 which forms a mixing chamber 38 open along its lower surface. A plurality of ceramic blocks 50 having a plurality of small through passages 42 are secured by any suitable means to each housing 36 thus forming the remaining wall of the chamber 38. The composition of the burner blocks 40 and the section and length of the passages 42 is such that combustion of the fuel-air mixture occurs on the outer surfaces of the 55 burners.

50 At one end the housing members 36 are provided with integral fuel-air inlet sections 44 which are preferably open at their top surfaces. An opening is provided in the rear wall of each of the sections 44 to accommodate a gas nozzle 45 which is connected by suitable piping to a source of gas under pressure and directs a jet of gas into the chamber 38 entraining air which enters the section 44 through its open top surface.

60 In operation a mixture of gas and primary air is forced through the passages 42 and burned in or on the outer surface of the blocks 40. Almost immediately after the 65

70 In operation a mixture of gas and primary air is forced through the passages 42 and burned in or on the outer surface of the blocks 40. Almost immediately after the

operation of the burners is initiated the lower surfaces of the ceramic blocks are heated to incandescence and emit radiant energy in the infra-red spectrum which is directed to the area to be heated by the duct assembly 24. It is a characteristic of burners of this type that the substantially flameless combustion appearing on or in the surface of the ceramic blocks is effected without secondary air supplied to the surface of the ceramic blocks. In fact it has been discovered in practice that random currents of secondary air supplied to the lower surface of the ceramic blocks may actually interfere with the combustion process and lower the temperature of the surface of the blocks thus materially reducing the efficiency of the burner. In recognition of this fact the present invention provides the duct assembly 26 which extends across the duct assembly 24 and which is effective to permit satisfactory evacuation of the products of combustion from the area at the lower surface of the ceramic blocks 40 while preventing the impingement of excess air currents on the combustion surfaces.

The rear wall and two side walls of the duct assembly 26 are formed by a sheet metal U-shaped channel 46 (Figure 3), the rear wall portion 48 being notched at 50 and 52 adjacent its opposite ends to permit the side wall portions 54 and 56 to be bent at right angles to the rear wall portion 48. An evacuation flue assembly 58 comprising a duct of rectangular section forms the front wall of the duct assembly 26 and is welded or otherwise suitably secured to the free ends of the duct end side walls 54 and 56. As shown particularly in Figure 1 the flue assembly 58 is bent upwardly to promote the flow of the hot combustion products out of the duct assembly 26 by convection.

Secured to the upper end of the flue assembly 58 by two spaced pairs of straps 60 is an arcuate shield 62. The shield permits substantially unrestricted flow of combustion products out of the flue assembly while preventing or substantially restricting the inward flow of air through the flue assembly and the entrance of rain or snow. The open end of the flue assembly 58 is further protected against the entry of air currents by shields 64 and 66 which are suitably secured to the top and bottom walls of the flue assembly 58 and project outwardly therefrom to points opposite the lateral edges of the shield 62. As best shown in Figure 3 all of the shield members 62, 64, and 66 extend the full length of the flue assembly 58 to provide maximum protection.

As best shown in Figure 4 a plurality of openings 68 are provided in the rear wall 48 of the duct assembly 26 to promote ventilation of the area around the burner elements by convection. These openings are protected from air currents by a sheet metal shield assembly 70 which extends the full length of the rear wall 48 of the duct assembly 26 and is secured along its lower edge to the duct member 25 and at its upper edge is bolted or otherwise detachably secured to a pair of straps 71 and 72 preferably welded to the wall 48. The opposite ends of the shield 70 are spaced a substantial distance outwardly of the shield assembly 28. Accordingly, if reverse flow occurs within the duct assembly 26 due to the positioning of the burner assembly or other factors the products of combustion will be vented outwardly of the ends of the shield assembly 28 so as to avoid contamination of the incoming primary air flowing into the burner. It will also be noted that under normal conditions all of the combustion products will be vented from the outlet of the flue assembly 58 so that there is no possibility of contamination of the primary air with combustion products.

The duct assembly 26 is completed by an access plate 76 pivotally mounted on the side wall 56 as at 78 over an access opening 80 to permit manual ignition of the burner. Where automatic ignition of the unit is provided for, the igniter assembly is preferably mounted in the opening 80.

It is an important feature of the invention that the duct assembly 26 is substantially entirely enclosed. In accordance with the present invention the bottom wall of the duct assembly is formed by a sheet of glass 82 which shields the combustion surface from air movements within the heat duct member 25. The glass panel 82 is preferably held in place by a plurality of clips 84 suitably spaced around the periphery of the panel. Ordinary lead borax glass, such as window glass, is quite transparent to infra-red radiation in the visible spectrum where wave lengths are less than one micron but becomes increasingly translucent to infra-red radiation in the longer wave lengths. In practice it has been found that most applications require the emission and transmission of infra-red radiation in wave lengths of approximately 3 microns to more than 8 microns. Accordingly ordinary window glass cannot be used in the burner without serious loss of efficiency. In accordance with the invention a silicon glass sold under the trade name of Vycor is utilized for the panel 82 since it has been found that this glass permits substantially complete transmission of radiant energy in the desired wave lengths.

The primary heat duct member 25, secondary ventilation duct assembly 26 and the burner assemblies are preferably secured together by a plurality of bolt and nut assemblies 86 located at points suitably spaced around the periphery of the assemblies. Substantial sealing of the duct 26 is effected by asbestos gaskets 88 and 90 which are clamped respectively between the upper surface of the duct assembly 26 and the frame structure 32 and between the lower surface of the duct assembly 26 and the flanged upper end of the heat directing duct member 25.

To provide a completely windproof burner assembly 35 the inlet area through which the primary combustion air enters the burner must be fully protected against winds approaching the burner from all direction to provide a constant pressure in the area surrounding the air inlet to thereby assure entrainment of combustion air 40 by the gas nozzles 45 at a substantially uniform rate.

Shield assembly 28 which has been provided for this purpose will now be described in detail with particular reference to Figures 5 and 6. As there shown shield 28 comprises a main dish-shaped cover plate 92 of elongated 45 form of sufficient width and length to enclose completely the air-gas inlet assemblies 44 of the burners 20 and 22. The rearward portion of the main shield member 92 is closed by a sheet metal baffle 94, the free edge of which is preferably disposed substantially directly over the rear edge of the air inlet assemblies 44 when the shield assembly is installed in the burner. Spaced from and substantially parallel to the free edge of the shield 94 are a pair of baffles 96 and 98 welded to the cover plate 92. A second pair of baffles 100 and 102 are also welded to the interior of the cover plate 92 and extend laterally of the cover plate from the forward edge thereof to a point approximately at the mid-point of the longitudinal baffles 96 and 98. As best shown in Figure 6 the bottom edges of the respective baffles 96, 98, 100 and 102 are coplanar and are spaced substantially above the lower edge of the cover plate 92. The shield assembly is completed by corner plates 104 and 106 which extend around the front corners of the shield substantially from the ends of the baffles 100—96 and 102—98 and project below the lower edge of the cover plate 92. Shield assembly 28 is preferably held in place by a pair of screws 108 threaded directly into the burner castings.

The T-shaped assemblies formed by the respective baffles 96 and 100, and baffles 98 and 102, serve in operation as direction vanes to guide the primary air into the air inlet sections 44. It has been discovered that these vanes minimize turbulence of the air entering the burner and increase the efficiency with which the inspiration of primary air is effected.

75 The baffle 94 seals the space in the region of the rear

ward lateral edge of the shield assembly 28. It prevents the establishment of a vacuum within this area of the shield which actual experiments have shown is otherwise caused by wind blowing parallel to the lower edge of the cover plate 92. The baffles 104 and 106 serve essentially the same purpose as the baffles 96—102, and are particularly effective when the ambient wind blows diagonally across the corners of the cover plate 92.

Together the baffles prevent turbulence in the region of the primary area intake and establish and maintain substantially uniform air pressures in this region to promote uniform and non-turbulent inspiration of primary air thereby maintaining high burner efficiency even under adverse ambient conditions.

From the foregoing it will be apparent that the above-stated objects and advantages of the invention have been attained by the provision of improved burner assemblies which are substantially completely windproof and are thus operable with good efficiency under conditions which preclude the satisfactory operation of prior burners.

The invention may be embodied in other specific forms without departing from the spirit or essential characteristics thereof. The present embodiment is therefore to be considered in all respects as illustrative and not restrictive, the scope of the invention being indicated by the appended claim rather than by the foregoing description, and all changes which come within the meaning and range of equivalency of the claim are therefore intended to be embraced therein.

What is claimed and desired to be secured by United States Letters Patent is:

A burner assembly comprising means forming at least one mixing chamber for gaseous fuel and air, a burner element forming one wall of said mixing chamber, said burner element being disposed below said mixing chamber when the burner is in use, said mixing chamber having an air inlet opening at one end, a heat directing duct assembly leading away from said burner element in a

direction generally normal to the surface of said burner element, an additional duct assembly extending generally parallel to the surface of said burner element across said heat directing duct assembly adjacent said burner element, one end of said additional duct assembly projecting beyond the end of said mixing chamber remote from said air inlet opening and being elevated above the opposite end of said additional duct assembly when the burner is in use whereby products of combustion are exhausted at a point remote from said air inlet opening to prevent contamination of said air inlet opening, a shield assembly comprising a dish-shaped member extending over said air inlet opening, the open side of which faces said air inlet opening, a baffle having one edge secured to one lateral edge of said dish-shaped member and extending inwardly therefrom parallel to the bottom wall of said dish-shaped member, a pair of baffles extending around the respective corners of said dish-shaped member and projecting from the lower edge of said dish-shaped member, and air directing vanes projecting from said bottom wall of said dish-shaped member toward said air inlet opening.
